UNITED STATES PATENT OFFICE.

VICTOR G. ERICSON, OF WAUKEGAN, ILLINOIS, ASSIGNOR TO VICTOR LOCK WORKS,
OF NORTH CHICAGO, ILLINOIS, A COMMON LAW TRUST.

COMBINATION LOCK.

1,402,221.

Specification of Letters Patent.

Patented Jan. 3, 1922.

Application filed April 21, 1921. Serial No. 463,314.

To all whom it may concern:

Be it known that I, VICTOR G. ERICSON, a citizen of the United States of America, and a resident of Waukegan, county of Lake, 5 and State of Illinois, have invented certain new and useful Improvements in Combination Locks, of which the following is a specification.

This invention relates to combination locks suitable for all the general uses of such devices. The object of the invention is to provide a combination lock the knob of which when the lock is applied to such devices as table or desk drawers will serve the 10 combined functions of setting the permutation rings or tumblers operating the latch or bolt by motion in the direction of its axis, and also serve as a drawer pull or handle.

20 A further object of the invention is to provide a combination lock which can be manipulated merely by the sound or feel of moving parts when arriving at releasing position. This object of the invention is 25 accomplished by placing the spring-released latch or bolt under the control of a longitudinally movable spindle attached to the knob of the lock.

The objects of the invention are accomplished by a device such as illustrated in the drawings, wherein—

Fig. 1 is a plan view of a lock constructed according to this invention.

Fig. 2 is a sectional view taken on the 35 line 2—2 of Fig. 4.

Fig. 3 is a sectional view taken on the line 3—3 of Fig. 4.

Fig. 4 is a transverse vertical section of the lock showing the parts thereof in normal locking position.

Fig. 5 is a transverse vertical section showing the knob moved outwardly and the bolt released.

Fig. 6 is a horizontal sectional view taken 45 on the line 6—6 of Fig. 4.

Fig. 7 is a detail in perspective of the base plate of the lock.

Fig. 8 is a detail in perspective of the bolt.

The structure illustrated in the drawings 50 comprises a base plate and a cylindrical casing for enclosing the movable elements of the lock. Centrally mounted in this casing with its head projecting therefrom is a spindle and knob which is rotatable for the 55 purpose of setting the permutation disks and is also movable to limited extent in an axial

direction for camming the bolt or latch into locking position or releasing it so that it may move to unlocking position under spring action. By means of this structure 60 the spindle of the rotatable knob normally retains the bolt immovable in locking position and since no spring-operated elements normally engage the permutation rings, the setting of these rings by rotating the bolt 65 will not become apparent by feeling or listening for any clicking action. When the knob is drawn to its outer position it becomes ineffective for changing the setting of the permutation rings.

The structure as illustrated in the drawings comprises a base plate 1 having an upstanding slotted flange 2 through which the bolt or latch 3 projects. Mounted on the base plate 1 is a disk-shaped bearing element 4 70 having a central boss 5 for receiving the spindle 6 of the rotatable setting knob 7. The casing 8 through which the knob projects is secured to base plate 1 by bent lugs 9 passing through apertures in the base plate. 80 The outer surface of the boss 5 serves as a bearing for the permutation disks 10 and 11. These are spaced apart by a washer 12 which is prevented from rotating by a projection thereon fitting the spline 13 in boss 5. A 85 similar washer 14 serves to prevent rotation of the ring 10 through surface friction with a similar ring 15 fast to the hub 16 of knob 7. The locking bolt 3 is guided in a slot 17 in the bearing member 4 and is provided 90 with a lug 18 normally projecting into a recess 19 in the boss 5. The boss 5 is also at the location of recess 19 provided with a radial recess 20 for receiving a spring 21 bearing against lug 18 on the bolt 3, urging 95 the same to unlocking position. Such movement of the bolt 3 is normally prevented by the spindle 6, which projects through an aperture 22 in the bolt. Such movement of the bolt 3 is also prevented by the 100 inner surfaces of the permutation rings 10 and 11 but these rings have a recess 23 at one point on their inner edges to receive the lug 18 of bolt 3 when the same is permitted to move to unlocking position. The fixed 105 spacing washers 12 and 14 are similarly recessed.

The setting knob 7 is normally held in its inner position by a spring 24 bearing between the inner surface of casing 8 and the 110 surface of disk 15 rigid with the setting knob. A pin 25 on disk 15 coacts with a pin

26 on permutation ring 10 and this pin also coacts with a pin 27 on ring 11. The location of the rings in the permutation rings with respect to the pins thereon determines what number on the dial 28 on casing 8 must be indicated by the pointer 29 for the recesses in the rings to register with lug 18 on bolt 3. The pointer 29 is fixed to the setting knob 7.

10 Axial movement of the setting knob 7 controls the operation of bolt 3 and for this reason the bolt at the point of its aperture 22 has an inclined surface 30 for coacting with the lower curved end of the spindle 6.

15 Thus if the notches in the permutation rings register with the lug 18 on bolt 3, an inward movement of the setting knob from the position indicated in Fig. 5 to that shown in Fig. 4 forces the bolt outwardly into locking position.

20 When the setting knob is in its outer position spring 21 may force the locking bolt into releasing position but only when the recesses in the permutation rings register with lug 18.

25 In operating the lock the setting knob 7 is rotated first in one direction and then in another, as usual with combination locks, until the recesses 23 in all the setting rings are alined with lug 18 on the bolt 3. Such motion can be imparted to the permutation rings only when the setting knob is in its inner position where pin 25 will coact with pin 26. Then when the knob is released and moves outwardly under the action of spring 30, the bolt 3 is driven to unlocking position by the spring 21. To again set the mechanism in locking position it is only necessary to depress the setting knob 7 and thereby through engagement of the spindle 6 with the cam surface 30 on the bolt forcing the bolt to locking position. Then a rotation of the knob 7 rotates the permutation rings into position to retain the bolt 3 in its outer position by blocking inward motion thereof in the lug 18.

50 Although but one specific embodiment of this invention has been herein shown and described, it will be understood that numerous details of the construction shown may be altered or omitted without departing from the spirit of this invention as defined by the following claims.

I claim:

55 1. A combination lock, comprising a supporting structure, a locking bolt slidably mounted in said structure, permutation elements for releasing or retaining said bolt in locking position, a rotatable setting knob for imparting movement to said permutation elements, said setting knob being also movable in an axial direction and actuating said bolt by its axial movement.

60 2. A combination lock, comprising a supporting structure, a locking bolt slidably mounted therein, a spring for normally urg-

ing said locking bolt into unlocking position, permutation elements for normally preventing action of said spring, and a rotating setting element adapted to shift said permutation elements into position for releasing the locking bolt, said setting knob being axially movable and arranged to actuate said bolt by said axial movement. 70

3. A combination lock, comprising a supporting structure, a setting knob mounted 75 therein for rotation and axial movement, a locking bolt slidably mounted in said supporting structure for motion at right angles to the axial motion of the setting knob, co-acting cam surfaces on said locking bolt and setting knob, and permutation elements movable by rotation of the setting knob and controlling motion of the locking bolt. 80

4. A combination lock, comprising a supporting structure, a setting knob mounted 85 therein for rotation and axial movement, a locking bolt slidably mounted in said supporting structure for motion at right angles to the axial motion of the setting knob, co-acting cam surfaces on said locking bolt and setting knob, permutation elements movable by rotation of the setting knob and controlling motion of the locking bolt, and a spring 90 for normally urging the locking bolt to unlocking position. 95

5. A combination lock, comprising a supporting structure, a plurality of permutation elements rotatably mounted on said structure, a setting knob rotatably mounted on said structure and arranged to coact with said permutation elements, said setting knob being axially movable into and out of coacting relation with the permutation elements, and a locking bolt controlled by said permutation elements, said locking bolt being actuated by the axial movement of said setting knob. 100

6. A combination lock, comprising a supporting structure, a plurality of permutation elements rotatably mounted on said 110 structure, a setting knob rotatably mounted on said structure and arranged to coact with said permutation elements, said setting knob being axially movable into and out of coacting relation with the permutation elements, 115 a spring for normally urging the setting knob into coacting relationship with the permutation elements, and a locking bolt controlled by said permutation elements, said locking bolt being shifted to locking 120 position by the axial movement of said setting knob.

7. A combination lock comprising a support, a permutation ring rotatably mounted on said support and having a recess formed 125 on its inner edge, a locking bolt slidably mounted on said support and having a part arranged for engagement with the inner edge of said ring and with said recess, and a rotatable setting knob for imparting move- 130

ment to said permutation ring and locking bolt.

8. A combination lock comprising a support, a permutation ring rotatably mounted on said support and having a recess formed on its inner edge, a locking bolt slidably mounted on said support and having a lug arranged for engagement with the inner edge of said ring and with said recess,

10 means normally urging said lug into engage-

ment with said recess for retaining said bolt in unlocking position, and a rotatable setting knob for imparting movement to said permutation ring, said setting knob being also movable in an axial direction to shift 15 said bolt into locking position out of engagement with said recess.

Signed at Waukegan this 18th day of April 1921.

VICTOR G. ERICSON.
